UNITED STATES PATENT OFFICE.

MARSHALL I. WILLIAMSON, OF BALTIMORE, MARYLAND.

VIBRATORY-DIAPHRAGM CONTROLLER.

1,340,471.

Specification of Letters Patent. Patented May 18, 1920.

Application filed May 13, 1919. Serial No. 296,769.

To all whom it may concern:

Be it known that I, MARSHALL I. WILLIAMSON, a citizen of the United States, residing at Baltimore city, State of Maryland, have 5 invented certain new and useful Improvements in Vibratory-Diaphragm Controllers, of which the following is a specification.

This invention relates to improvements in instruments that are equipped with vibratory diaphragms, whether for the purpose 10 of producing or reproducing sound or not, the object of the invention being to provide an improved means for controlling the vibrations of the diaphragms in such instruments.

A further object of the invention is to provide a controlling means of the character set forth, which is entirely independent of the elements or forces which produce the vibrations of the diaphragms.

A further object of the invention is to provide a controlling means of the character set forth, which is extremely simple in construction, economical to manufacture and 25 highly efficient in operation.

With the foregoing and other objects in view, which will appear as the description proceeds, the invention consists in the novel features of construction and combination of 30 parts which will be more fully described hereinafter and particularly pointed out in the claim.

Through experimental work and study I have discovered that while slight pressure, 35 often in fact mere contact at or about the center of a vibrating diaphragm renders it for the time either nearly or completely inactive, pressure near the edge of the diaphragm has little or no effect upon its activity, though even such pressure when sufficiently increased accomplishes a noticeable decrease in the activity of the diaphragm, and complete inaction may be effected by still greater pressure especially by bringing 40 it nearer the center of the diaphragm. The object of the present invention, therefore, is to provide means for controlling the vibrations by pressure on the diaphragm and so regulating and maintaining such pressure 45 that an arbitrary control over the diaphragm's vibrations may be accomplished which in the case of sound producing instruments or machines would result in a corresponding control over the volume of sounds 50 produced.

In the drawings accompanying and forming a part of this specification.

Figure 1 is a side view, partly in section, 60 of a sound-receiving instrument having my improved controller applied thereto, the instrument being broken away at the rear thereof;

Fig. 2 is a front end elevation thereof; and

Fig. 3 is a perspective view of a flexible 65 pad forming one of the essential parts of the present invention.

The same characters of reference designate the same parts in the several different figures of the drawings.

Referring to the drawings, 2 designates an 70 ordinary telephone receiver having the usual coils 3 and magnetic vibrators 4, and the usual diaphragm 5 which vibrates in response to the fluctuating magnetic force of the vibrators 4, the coils and vibrators being 75 mounted in a housing 6 of bell shape and on the outer end of which the diaphragm is seated and clamped thereto by means of a shoulder 7 carried by an annular member or ring 8 which is threaded on the end of the 80 receiver. The ring 8 is provided with a second interior circumferential shoulder 9 at its outer end, and the space between the shoulder 7 and the shoulder 9 is threaded for coöperation with a cap or ear piece 10. 85

An annular or washer-like pad 11 of flexible material, such for instance as cork, felt, rubber, paper or other suitable material is mounted within the circumferential shoulder 7 and is held centrally there- 90 within by engagement with the cap 10. When not under pressure the pad contacts only at its extreme outer circumferential edge with the diaphragm, its inner side being inclined slightly, as shown, from its 95 outer toward its inner circumference, while its outer side is flat and is adapted to be engaged by the cap 10. By this construction it will be seen that by rotating the cap so as to press with greater force on the pad, 100 the latter will be forced into greater contact with the diaphragm from the outer circumference thereof toward the center and that in such manner the vibrations of the diaphragm may be controlled to any 105 desired extent. For example, when it is desired to produce the maximum volume of sound the cap 10 is rotated so as to move it away from the pad thus lessening the latter's contact and pressure upon the dia- 110

phragm, while when the minimum volume is desired it is rotated so as to carry it toward the pad to the extreme of its inward movement thereby increasing the contact 5 and pressure of the pad upon the dia- phragm. In other words, when the cap is moved outwardly as described the pad gradually assumes its normal shape thus gradually lessening its contact with the dia- 10 phragm and increasing the vibrating area of the latter until at the extreme outward movement of the cap, which is determined by the shoulder 9, the only contact of the pad with the diaphragm is at the extreme 15 circumference of both, in which position the pad offers least resistance to the full activity of the diaphragm thus permitting the full volume of sound whereas when the cap is moved inwardly, it gradually com- 20 presses the pad so that its contact with the diaphragm is gradually increased from its outer circumference inwardly thus gradu- ally decreasing the vibrating area of the diaphragm until, if the pad is wide enough 25 complete inaction of the diaphragm is ac- complished and thus the complete absence of sound.

The front of the annular member or ring 8 may be provided with designations, such 30 as "Loud", "Medium" and "Soft", and the outer face of the cap 10 with an arrow or similar mark for indicating the proper re- lation between the cap and ring to produce the volume of sound desired. The edge of 35 the cap may be roughened, as shown at 12, to provide a grip to assist in turning the cap. The inner face of the pad is prefer- ably scored as shown at 13 to prevent it 40 adhering to the diaphragm after pressure has been withdrawn. The outer surface of the pad should be substantially stiffened so that it will remain always flat against the cap; in fact it may be found desirable to

have the entire outer surface of the pad securely fastened to the cap so as to pre- 45 vent accidental or undesired shifting or change of position.

While I have described in detail the structure herein illustrated, it will be under- 50 stood that I do not thereby limit my inven- tion to the precise features of construction shown, as I am aware that many mechani- cal changes and modifications may be made therein without departing from the spirit 55 and scope of the invention as set forth in the claim hereto appended.

Having thus described my invention, what I claim is:

In a telephone receiver, a housing, a vi- 60 bratory diaphragm seating on the outer end of the housing, an ear piece over the dia- phragm, a ring carried by said end of the housing and having an internal shoulder engageable with the diaphragm adjacent to its periphery for clamping the same to the 65 housing end, said ring also having a second internal shoulder and being internally screw- threaded between said shoulder and the first- 70 mentioned shoulder, the aforesaid ear piece having a rear portion which is screwed into the aforesaid threaded portion of the ring and is adjustable between the shoulders, and an annular member between the diaphragm and the ear piece and engageable with the 75 former adjacent to its periphery, said ear piece being adjustable to force the afore- said member into contact with the dia- phragm to a greater or less extent radially thereof, thereby to vary the diameter of the vibratory portion of the diaphragm. 80

In testimony whereof I affix my signa- ture in the presence of two witnesses.

MARSHALL I. WILLIAMSON.
